UNITED STATES PATENT OFFICE.

MARTIN HEEREN, OF NEWTON, IOWA.

TRACK CHOCK FOR CAR WHEELS.

Application filed August 25, 1927. Serial No. 215,395.

The invention relates to a chock adapted to be seated on a railroad rail to be engaged by the car wheels to stop a car in place on a siding, and has for its object the provision 5 of a device of the character stated that may be effectively seated on the rail and provided with an upstanding pedestal carrying a removable and replaceable brake shoe that forms a stop to engage the tread of the wheel 10 and also to form a brake to stop the rotation of the wheel.

The invention will be described in detail hereinafter and will be found illustrated in the accompanying drawings, in which

15 Figure 1 is a side view in elevation of the improved chock showing it applied to a railroad rail, suggested in broken lines, the car wheel being also indicated in broken lines,

20 Figure 2 is a top plan view of the chock,
Figure 3 is a longitudinal sectional view
of the chock,

Figure 4 is an end view,

Figure 5 is a transverse sectional view on a plane indicated by the line 5—5 of Figure 1,

25 Figure 6 is a top plan view of the channelled member,

Figure 7 is a similar view of the channelled plates, and

30 Figure 8 is a top plan view of the pedestal member, the brake shoe being removed.

In the drawings similar reference characters will be used to designate corresponding parts throughout the several views.

The improved track chock comprises a 35 channelled member 1 having downwardly turned side flanges 2. One end portion of the member 1 is upwardly offset as shown at 3 to receive a plate 4 that is secured thereto by means of rivets, or other suitable fastenings 5, and having side flanges 6 alined with flanges 2, channelled member 1 and plate 4 being adapted to seat on a railroad rail suggested at A. The free end of plate 4 is tapered as shown at 7 to form a tread for car 40 wheel B to carry the wheel up off of the rail onto the plate 4, and the offset portion 3 has its upper edge inclined to provide a tread for the wheel to permit it to ride up on to said offset portion. The end of channelled member 1 remote from the offset portion 3, is provided with a tongue that is upturned as shown at 8 and has its extremity returned to form a hook 9.

Secured to channel member 1 is a pedestal 45 member 10 having a base plate 11 seated on said channelled member and secured thereto

by means of bolts 12 or other suitable fastenings, said base plate 11 having an upturned end 13 to engage the upturned tongue 8, and has its extremity seated in the hook 9, this 60 structure providing for securely fastening the pedestal member 10 to the channelled member 1 and serving to strengthen the engagement by the bolt, to prevent shearing of the bolt under undue stress in the use of the 65 device. 14 indicates the pedestal carried by the base 11 and recessed as shown at 15, the upper edge of the pedestal being inclined as shown at 16 to support a brake shoe 17 having a flange on its upper and side edges, 70 designated 18 that encloses the upper portion of the pedestal, said brake shoe having a downwardly extending tongue 19 provided with a slotted opening 20 to receive a pin 21 secured to the walls of the pedestal to hold the brake shoe in position. The function of said slotted opening 20 is to permit adjustment of the brake shoe when engaged by the 75 tread of the wheel to prevent breakage of the shoe and to insure engagement of the bearing surface thereof with the wheel tread. 22 indicates a reinforcing brace member connecting the forward end of the base 11 with the upper portion of the pedestal 14.

In use it will be understood that the device is placed upon a railroad rail, such as suggested at A, in the position in which it is desired to stop the progress of a car in being located on a siding, and it will be understood that when the forward car wheel encounters the chock it will ride onto the plate 4 and from thence to the offset portion 3 of the channelled member 1, and the wheel will engage the brake shoe 17, thus stopping the wheel from further progress, and the brake shoe 95 will also serve to prevent spinning or rotating of the wheel. It will also be understood that by having the parts dismemberable as hereinbefore described that repair of the chock may be readily effected by replacing 100 imperfect parts with replacement parts, this being particularly applicable to the brake shoe 17 that may be readily removed and replaced should it become worn or broken by contact with the wheel.

105 What is claimed is:—

A track chock for car wheels, comprising a channelled member having an upwardly offset portion at one end, the other end of said member up-turned and its extremity rebent to form a hook, a pedestal secured to said channelled member and having an up-turned 110

end to engage the first-mentioned up-turned portion and engaged in said hook, a channelled plate having a tongue secured under the upwardly offset portion of the first-mentioned member, said channelled member and plate being adapted to seat on a railroad rail, the pedestal provided with a recess, a brake

shoe, a tongue on said brake shoe engaging in said recess and having a slotted opening therethrough, and securing means engaging said pedestal and through said slotted opening.

In testimony whereof I affix my signature.

MARTIN HEEREN.
